UNITED STATES PATENT OFFICE.

CHARLES H. PATRICK, OF CHICAGO, ILLINOIS.

SURGICAL CHAIR.

SPECIFICATION forming part of Letters Patent No. 717,612, dated January 6, 1903.

Application filed March 24, 1902. Serial No. 99,823. (No model.)

To all whom it may concern:

Be it known that I, CHARLES H. PATRICK, a citizen of the United States, residing at Chicago, in the county of Cook and State of Illinois, have invented certain new and useful Improvements in Surgical Chairs; and I do hereby declare the following to be a full, clear, and exact description of the invention, such as will enable others skilled in the art to 50 which it appertains to make and use the same, reference being had to the accompanying drawings, and to the figures of reference marked thereon, which form a part of this specification.

The object of this invention is to form a folding surgical chair particularly useful in administering rectal or vaginal douches or injections.

A further object is to form a folding chair 55 of the class stated which will occupy comparatively little space when folded and which may be adjusted when in use to give any ordinary degree of pelvic elevation.

An embodiment of the invention is illustrated in the accompanying drawings, in which—

Figure 1 is a side elevation of the chair with the back lowered. Fig. 2 is a side elevation with the back raised. Fig. 3 is a side 60 view of the chair when folded. Fig. 4 is a top view of the chair-seat, and Fig. 5 is a vertical section thereof.

Referring specifically to the drawings, 6 indicates the spreading legs of the chair, which 65 are pivoted together at the top, as at 6^a. The chair-seat 7 swings on the same pivot 6^a and has a leg-rest or extension 7^a, hinged at 7^b to the front edge thereof. A spring-catch 7^c, carried by the extension, engages the seat to 70 hold the leg-rest straight therewith when desired. The back is indicated at 8 and is hinged to the seat by a bolt 9, which is threaded to receive a hand clamping-nut 9^a. The side frames of the back are slotted, as at 9^b, 75 to receive the bolt and to permit the necessary adjustments. By means of the nut, bolt,

and slot the back may be inclined at various degrees to the seat and clamped at such adjustment. The lower ends of the side frames of the back stop against the blocks 10, attached to the rear legs, and by altering the inclination of the back the seat may be made to tilt backward, as desired to effect pelvic elevation.

The seat is provided with a cushion 11 and 80 an opening 12, through which opening the cushion-cover 11^a is made to extend to form a drain leading to the tube 13, which may be conveniently made to discharge into a pail 13^a. The seat and its cushion are made to 85 incline from all sides to the opening 12 to direct the liquid thereto, and the liquid will not run down the back even though the back be lower than the seat.

6^b indicates folding braces connecting the 90 legs.

What I claim as new is—

1. A chair comprising legs pivoted together at the top, a tilting seat pivoted at the top of the legs and having a drain-opening therein, 70 and a back joined to the seat and having its lower end in adjustable supporting contact with the legs.

2. A surgical chair having a tilting seat and back, with a drain-opening in the seat, and a 75 cushion on the seat behind the opening and inclined downwardly and forwardly thereto.

3. In a surgical chair, a tilting seat having an opening, and a cushion on the seat ridged around behind the opening to direct liquid 80 thereto, the cushion-cover extending through the opening to form a discharge-spout.

4. A chair comprising legs, a rocking seat pivoted thereon having a forward extension hinged thereto, and a back hinged to the seat 85 behind its pivots and having a projecting portion in supporting contact with the legs.

CHAS. H. PATRICK.
